BURNER SAFETY CONTROL
Anthony A. Fennell, Homewood, Ill.
(379 E. 147th St., Harvey, Ill.)
Filed July 19, 1957, Ser. No. 673,016
3 Claims. (Cl. 158—123)

The present invention relates to a novel control system, and more particularly to a novel system adapted to control burners and the like.

Industrial furnaces are frequently provided with a plurality of burners which utilize gas, oil or other suitable fuels. Some means must be provided for shutting off all burners if any one of them goes out so that unburned fuel is not introduced into the furnace from such extinguished burners and subsequently ignited by one of the other burners. It will be appreciated that fuel ignited in this manner might well cause an explosion. Various control systems have heretofore been proposed, which systems usually incorporate a separate detector for each burner capable of sensing the presence or absence of a flame, and a separate control circuit for each detector. Such heretofore proposed control circuits are costly so that the cost of a furnace installation is high especially when the furnace has a considerable number of burners.

An important object of the present invention is to provide a novel control system for a plurality of burners, which system is materially simplified and eliminates duplication of many parts heretofore believed to be necessary so that the system may be installed and maintained relatively easily and economically.

A more specific object of the present invention is to provide a novel control system of the above described type which utilizes separate detectors or flame sensing devices for each burner and which is greatly simplified as compared with heretofore proposed systems in that it includes only a single control circuit successively and separately connectable with each of the detectors or sensing devices so as to accomplish periodic inspection of each of the burners.

Still another object of the present invention is to provide a novel control system of the type mentioned in the preceding paragraph which is constructed so as to shut off the burners in the event of failure of the system to proceed with successive inspection of the burners.

Other objects and advantages of the present invention will become apparent from the following description and the accompanying drawings wherein—

FIG. 1 is a schematic view showing a control system incorporating features of the present invention;

FIG. 2 is a schematic view showing a slightly modified control system;

FIG. 3 is a schematic view showing another slightly modified form of the present invention;

FIG. 4 is a detailed diagrammatic showing of the fuel supply control relay employed in the system of FIG. 1;

FIG. 5 is a detailed diagrammatic showing of the sensing circuit relay incorporated in the modified control system of FIG. 2; and

FIG. 6 is a detailed diagrammatic showing of the pulse timer employed in the modified form of the invention illustrated in FIG. 3.

In FIG. 1 there is shown a control system 10 for controlling burners 12, 14, 16, 18, 20 and 22 in a furnace or the like. While six burners have been shown for the purpose of illustrating the present invention, it will be appreciated that the advantages of the present invention may be realized when the control system is constructed for use with at least two burners and any desired larger number of burners. Fuel is supplied to the burners from a common pipe 24, and a valve 26 is connected in

2

this pipe. This valve is a spring biased solenoid operated valve of known construction such that when the solenoid 28 thereof is energized the valve is open and when the solenoid is deenergized spring means causes the valve to close.

Adjacent the burners are detectors or sensing devices 30, 32, 34, 36, 38 and 40. These detecting or sensing devices are of known construction and may, for example, be of a type which generates an electric signal in response to heat or light from the flame when the burner is lit. Alternatively, the sensing or detecting devices may be of the resistance type which changes electricity conducting characteristics in accordance with temperature.

In accordance with a feature of the present invention the control system is provided with only a single relay 42 for controlling the fuel shut off valve 26. The relay is preferably of a fast acting type and of known construction and has terminals connected with the solenoid 28 by wires 44 and 46. Power is supplied to the relay through lines 48 and 50. Safety switch means generally designated by the numeral 52 is inserted in the line 50 for shutting off power to the relay and thereby causing the fuel shut off valve to close in the event of a failure of a portion of the control system as described more fully hereinbelow.

The control system is provided with switch means generally designated by the numeral 54 for successively and separately connecting each of the sensing devices 30—40 with the relay 42. It will be appreciated that the switch means 54 may be constructed in various ways, but for the purpose of illustrating the present invention the switch means 54 is provided with a plurality of fixed switch contacts 56, 58, 60, 62, 64 and 66 cooperable with movable contacts 68, 70, 72, 74, 76 and 78. The fixed contacts are respectively connected with the relay by common wires 80 and 82 and branch wires 84, 86, 88, 90, 92 and 94. The movable contacts are respectively mounted on movable fingers 96, 98, 100, 102, 104 and 106 which are connected with one terminal of the sensing devices 30—40 respectively by wires 108, 110, 112, 114, 116 and 118. Other terminals of the sensing devices are connected to the relay by wire 120 and branch wires 122, 124, 126, 128, 130 and 132.

Considering FIG. 4, the relay 42 will be seen to include a coil 200 which is connected between line 48 and wire 80. Energization of coil 200 causes a magnetic element 202 to operate a movable contact 204, contact 204 being electrically connected to both line 50 and wire 120. Relay 42 also includes a fixed contact 206; and when magnetic element 202 directs contact 204 to make electrical connection with contact 206, a circuit is completed from line 50, through the contacts 204 and 206 to wire 46, through solenoid 28 and through wire 44 to line 48. As will be recognized, coil 200 remains energized to preserve completion of the circuit through contacts 204 and 206 to the operating solenoid 28 of valve 26 only so long as switch means 54 and safety switch means 52 continue the circuit from line 50 to wire 80 in a completed condition.

60 The switch means 54 is provided with a plurality of rotatable cams 134, 136, 138, 140, 142 and 144 respectively engageable with cam elements 146, 148, 150, 152, 154 and 156 on the fingers for positioning the fingers to open or close the switch contact points. The rotatable cams are all fixed on a shaft 158 which is continuously driven by an electric motor 160. The rotatable cam members are constructed and fixed on the shaft 158 so that the pairs of switch contact points are successively opened and closed and so that only one pair of the contact points is closed at one time to accomplish inspection of a given burner. The construction may be such that there will be a slight overlapping of the periods during

which successive pairs of points are closed so as to prevent the relay from closing the shut off valve as the relay is switched from one sensing device to the next. It will be appreciated that since the motor 160 is continuously operated the cycle of opening and closing of the switches will be continuously repeated. As a result each of the detector devices will be connected periodically with the relay.

It will be appreciated that in the event one of the burners goes out, its associated sensing or detector device will signal the relay 42 upon being periodically connected with the relay so that the relay will function to close the valve 26. In order to prevent an undue lapse of time between the instant a burner goes out and the moment in which its associated sensing device is subsequently connected with the relay, it is necessary to rotate the cam shaft 158 at a speed which enables the entire cycle to be completed in a relatively short time. While this time interval may be varied somewhat for different installations, it should be as short as possible and as a result each burner will be inspected for no more than a few seconds during each scanning cycle. Thus the relay 42 must be a fast operating type which is capable of causing the fuel shut off valve to be closed upon receiving a brief signal from one of the scanning devices and before the next scanning device is connected with the relay.

In the event of a failure of the motor 160 or some other mechanical breakdown which would cause the cam shaft 158 to stop it would be possible for a single sensing or detector device to remain connected with the relay 42. Under such condition it might be possible for a burner associated with another sensing device to go out without being detected. However, in accordance with a feature of the present invention this possibility is eliminated by the provision of the above mentioned switch means 52. In this embodiment, the switch means 52 has a fixed contact 162 and a cooperable contact 164 which is axially movable on a rotatably supported shaft 166. A fly weight governor type device 168 is driven by the shaft 166 for raising the contact 164 into engagement with the contact 162. The shaft 166 is in turn driven from the cam shaft 158 through bevel gears 170 and 172. Thus, in the event the cam shaft 158 is stopped for any reason, the shaft 166 will also be stopped and the fly weight device will cause the contact 164 to be disengaged from the contact 162. When this occurs power to the relay 42 is shut off and the fuel valve 26 is closed.

FIG. 2 shows a slightly modified form of the present invention which is similar to the above described control system as indicated by the application of identical reference numerals with the suffix "a" added to corresponding elements. This embodiment differs primarily in the construction of the safety switch means. More specifically, the safety switch means 52a comprises a relay 174 for connecting portions of the wire 50a only when electricity is supplied for energizing the relay through the wires 176 and 178. These wires are connected with terminals of a small generator 180 which is driven from the cam shaft 158a through gears 170a and 172a. Thus, whenever the cam shaft 158a is stopped, the generator 180 is stopped so that the relay 174 is deenergized and the relay 42a is disconnected from the main power source.

With specific reference to FIG. 5, the relay 174 will be seen to include a coil 208 which is connected in electrical series circuit with generator 180 by the wires 176 and 178. The relay 174 also includes a magnetic element 210 which is controlled by the coil 208 to actuate a movable contact 212. The movable contact 212 is arranged to coat with a fixed contact 214 in completing a circuit from line 50a, through the contacts 212 and 214 and through a wire 216 to the movable contact of relay 42a. As will be recognized, cessation of the operation of generator 180 serves to deenergize coil 208 whereby to open the circuit through contacts 212 and 214. This

in turn opens the circuit from line 50a through the contacts of relay 42a to the line 48a.

FIG. 3 shows another slightly modified form of the present invention which is similar to the above described structures as indicated by the application of identical reference numerals with the suffix "b" added to corresponding elements. This embodiment also differs primarily in the construction of the safety switch means 52b. In this embodiment the switch means 52b comprises a pulse type or periodically energized timer 182. Such timers are of known construction and usually include a holding circuit which must be periodically energized in order to prevent opening of the main power line contacts. In the present installation the timer holding circuit has terminals connected by wires 184 and 186 to a fixed contact 188 and a contact 190 on a movable finger 192. A cam 194 fixed on the cam shaft 158b is constructed so as to operate the movable finger 192 to close the contacts 188 and 190 periodically during each revolution of the cam shaft. Thus, if for any reason the cam shaft is stopped the timer will not be periodically energized and it will function to disconnect the relay 42b from the main power source.

Turning to FIG. 6 for a more detailed consideration of the pulse timer 182, line 48b will be seen connected to wire 184 through a coil 218 and to relay 42b through a fixed contact 220 and a movable contact 222. Coil 218 operates a magnetic element 224 to actuate the movable contact 222, magnetic element 224 being mechanically connected to an air dashpot 226. Movable contact 222 is biased normally to open the circuit through the contacts 220 and 222 by means of a tension spring 228. Thus, spring 228 biases the contacts 222 and 220 into open configuration whereas air dashpot 226 opposes this action in order to delay opening of the contacts for a short time interval after a deenergization of coil 218. As will be recognized, a failure in the periodic closing of contacts 188 and 190 opens the circuit from line 50b, through wire 186, wire 184 and coil 218 to the line 48b. Upon deenergization of coil 218 in this manner, spring 228 eventually overcomes the mechanical resistance of dashpot 226 to open the contacts 220 and 222. This opening of the circuit through contacts 220 and 222 in effect opens the circuit to the coil of relay 42b to which contact 222 is connected by a wire 230. A wire 232 connects the movable contact of relay 42b to the line 50b.

While the preferred embodiments of the present invention have been shown and described herein, it is obvious that many structural details may be changed without departing from the spirit and scope of the appended claims.

The invention is claimed as follows:

1. A control system for a plurality of burners comprising: valve means for operating said burners; relay means for regulating said valve means; circuit means for actuating said relay means in response to the condition of said burners, said circuit means including a plurality of sensing circuits connected in parallel and adapted to be individually associated with said burners external to the flames thereof, each of said sensing circuits including a sensor adapted to be disposed adjacent a burner and a switch connected in series with said sensor; rotatable shaft means; a plurality of cams affixed to said shaft means and arranged to operate said switches in a repetitive sequence; and means responsive to the rotation of said shaft means for de-energizing the circuit means upon cessation of rotation of any part of said shaft means.

2. A control system for a plurality of burners comprising: valve means for operating said burners; relay means for regulating said valve means; circuit means for actuating said relay means in response to the condition of said burners, said circuit means including a plurality of sensing circuits connected in parallel and adapted to be individually associated with said burners external to the flames thereof, each of said sensing circuits including a sensor adapted to be disposed adjacent a burner and a

normally open switch electrically connected in series with said sensor; rotatable shaft means; a plurality of cam means affixed to said shaft means and arranged momentarily to close said switches in a repetitive sequence; a power source; and control means connected in circuit between said source and said relay means, including a control switch operated by a cam on said shaft, said control means passing power to said relay means when said control switch is regularly and periodically closed by said cam, said control means blocking power to said relay 10 means upon interruption of the periodic operation of said control switch.

3. A control system according to claim 1 wherein said rotationally responsive means includes periodically energizable control means connected to said circuit means for 15 maintaining said circuit means connected to a power

source upon said control means being periodically energized, said rotationally responsive means further including means periodically operated upon rotation of said shaft means for periodically energizing said control means.
